US0D1036937S

(12) **United States Design Patent** (10) **Patent No.:** **US D1,036,937 S**
(45) **Date of Patent:** **** Jul. 30, 2024**

(54) **BOTTLE**

(71) Applicant: **Fidlock GmbH**, Hannover (DE)

(72) Inventors: **Florian Hüwel**, Hannover (DE);
Thomas A. Moeller, Reno, NV (US)

(73) Assignee: **FIDLOCK GMBH**, Hannover (DE)

(**) Term: **15 Years**

(21) Appl. No.: **29/814,800**

(22) Filed: **Nov. 9, 2021**

(30) **Foreign Application Priority Data**

May 28, 2021 (DE) 402021100492.0

(57) **CLAIM**

The ornamental design for a bottle, as shown and described.

DESCRIPTION

FIG. 1 is a top perspective view of a bottle showing our new design;

FIG. 2 is a left side view thereof;

FIG. 3 is a front view thereof;

FIG. 4 is a right side view thereof;

FIG. 5 is a rear view thereof;

FIG. 6 is a bottom plan view thereof; and,

FIG. 7 is a top plan view thereof.

The portions of the bottle shown in broken line form no part of the claimed design.

1 Claim, 7 Drawing Sheets
